UNITED STATES PATENT OFFICE.

JEFFERSON CLAUDE DEAGAN, OF CHICAGO, ILLINOIS.

XYLOPHONE.

1,293,722.

Specification of Letters Patent.

Patented Feb. 11, 1919.

Application filed October 24, 1917. Serial No. 198,271.

To all whom it may concern:

Be it known that I, JEFFERSON CLAUDE DEAGAN, citizen of the United States, residing at Chicago, in the county of Cook and 5 State of Illinois, have invented a certain new and useful Improvement in Xylophones, of which the following is a full, clear, concise, and exact description.

My invention relates to musical instruments 10 employing sound producing bars made of wood or metal or other vibrating material that are tuned to produce tones of a musical scale and resonators below or behind such bars. Such instruments are 15 termed xylophones. An increase in the normal temperature of the bars and resonators will sharpen the pitch of the resonators to bring them out of sympathy or unison with the tones produced by the bars 20 and a decrease from such temperature will flatten the pitch of the resonators. I effect compensation for impairment of the pitch of the resonators due to modifications in temperature by adjustment of the interrelation of the bars and resonators. This adjustment may be effected by simultaneously regulating the distances between the bottoms of the resonators and the bars or the effectiveness of the openings in the resonators 25 that are adjacent the bars.

In the preferred embodiment of the invention the resonators, as a group, are bodily moved toward and from the bars transversely of the bars whereby the bottoms of 30 the resonators are not only adjusted with respect to the bars but the spaces between the tops of the resonators and the bars are also regulated to modify the effectiveness of the openings in the resonators that are 35 adjacent the bars.

I will explain my invention more fully by reference to the accompanying drawing showing the preferred embodiment thereof in which Figure 1 is a plan view showing 40 an instrument of the xylophone type with an intermediate portion broken away; Fig. 45 2 is a view on line 2—2 of Fig. 1; Fig. 3 is a view on line 3—3 of Fig. 2, a bar and a resonator being shown by dotted lines; and Fig. 4 is a perspective view illustrating a 50 part of the adjusting means.

Like parts are indicated by similar characters of reference throughout the different figures.

55 The instrument includes sound producing bars 1 each provided with a tubular reso-

nator 2 beneath the same. These resonators are usually open at their upper ends and closed at their lower ends. The bars are so tuned that they will produce tones of 60 a musical scale. They are suitably mounted upon strings 3 that pass through eyes 4 that project upwardly from the side rails of a mounting frame 5. The end rails of the mounting frame carry eyes 6 to which the 65 strings 3 are secured. The mounting frame has depending portions 7 at the ends thereof. Ledges 8 are at the lower ends of the depending portions 7. Adjusting thumb screws 9 project downwardly through the 70 end rails of the mounting frame and are in threaded connection with such end rails. Adjusting thumb screws 10 project upwardly through the ledges 8 of the mounting frame and are in threaded connection 75 with such ledges. Each screw 9 desirably has a screw 10 in vertical alinement therewith. The resonators 2 are disposed between and are in fixed connection with the rails 11 that support the resonators. These rails 80 11 have downward continuations 12 that rest upon the upper ends of the screws 10, the screws 9 being turned into engagement with the top edges of the rails 11 to prevent the frame from rising.

85 The spaces between the rails 11 and the end rails of the mounting frame 5 and the spaces between the lower ends of the continuations 12 and the ledges 8 are sufficient to enable a bodily vertical adjustment of 90 the rails and the resonators coupled therewith to simultaneously vary the spaces between the resonators and bars thereby to compensate for the usual wide variations in 95 temperature that the instrument may encounter. The rails enter vertical slots 11¹ that guide them in their vertical movements.

Let it be assumed that the instrument is 100 adjusted to have the resonators in correct sympathy with the tones produced by the bars in a temperature of 68° Fahrenheit, it being understood that the screws 9 and 10 hold the resonators in such relation to the bars that the desired quantity of tones is producible. If the temperature rises sufficiently from 68° Fahrenheit to throw the resonators appreciably out of sympathy with the tones produced by the bars the resonators are bodily raised to put the resonators into 105 correct sympathy with the tones produced by the bars and if there is a sufficient decrease in temperature to throw the resonators 110

tors out of sympathy with the tones produced by the bars the resonators are lowered to bring the resonators into sympathy, these 5 adjustments being effected by the obvious manipulation of the screws 9 and 10. To guide the user, the rails 11 may carry indexes or pointers 13 movable over temperature scales 14 that have scale marks that correspond to different temperatures and 10 are located to indicate the places to which the indexes 13 are to be brought to compensate for changes in temperature. There is desirably an index 13 upon each end of 15 each rail 11 and a scale 14 for each index. The scale marks at the lower end of the instrument are wider apart than those at the upper end, the difference in the spaces between the scale marks at the two ends of the instrument corresponding to the variation 20 in lengths of the resonators. The scale marks are thus differently spaced at oppo-

site ends of the instrument because the adjustment must be greater at the lower than at the upper end thereof.

While I have herein shown and particularly described the preferred embodiment of my invention I do not wish to be limited to the precise details of construction shown as changes may readily be made without departing from the spirit of my invention, but having thus described my invention I claim as new and desire to secure by Letters Patent the following:—

A xylophone including a group of sound producing bars; a group of resonator elements for said bars; and mechanism for adjusting one of said groups toward and from the other transversely of the bars. 35

In witness whereof, I hereunto subscribe my name this twentieth day of October 40 A. D. 1917.

JEFFERSON CLAUDE DEAGAN.
